Primary Examiner — Kendra Leslie Hamilton*Assistant Examiner* — Elizabeth S Struble(74) *Attorney, Agent, or Firm* — GrayRobinson, P.A.(57) **CLAIM**

The ornamental design for a light therapy device, as shown and described.

DESCRIPTION

FIG. 1 is a top, front, right perspective view of a light therapy device, showing my new design; FIG. 2 is a bottom, front, left perspective view thereof;

FIG. 3 is a top plan view thereof;

FIG. 4 is a bottom plan view thereof;

FIG. 5 is a left side elevation view thereof;

FIG. 6 is a right side elevation view thereof;

FIG. 7 is a front elevation view thereof;

FIG. 8 is a rear elevation view thereof; and,

FIG. 9 is a top, front, right perspective view of the light therapy device, shown in a condition of use for clarity of disclosure.

In the drawings, the equal-length broken lines depict portions of the light therapy device that form no part of the claimed design. In FIG. 9, the broken lines showing a wrist band depict environmental subject matter only and form no part of the claimed design.

1 Claim, 6 Drawing Sheets(56)
